UNITED STATES PATENT OFFICE.

HASKELL H. TIMMONS AND ELBERT L. SMITH, OF FREDONIA, KANSAS.

MUSIC-LEAF TURNER.

1,024,916.

Specification of Letters Patent.

Patented Apr. 30, 1912.

Application filed August 22, 1911. Serial No. 645,404.

To all whom it may concern:

Be it known that we, HASKELL H. TIMMONS and ELBERT L. SMITH, citizens of the United States, and residing at Fredonia, in 5 the county of Wilson and State of Kansas, have invented certain new and useful Improvements in Music-Leaf Turners, of which the following is a specification.

This invention relates to music leaf 10 turners, and pertains especially to the class of spring operated devices for turning music leaves.

The object of the invention is to provide 15 novel and peculiar construction and arrangement of the parts of a music leaf turner affording means for operating the same either by hand or by foot pressure.

A further object of the invention is to provide a music leaf turner adapted to be 20 operated either by hand, or by foot pressure and comprising a plurality of foldable and extensible arms operated by a pair of spring controlled slidable levers connected with a pair of foot levers.

25 A still further object of the invention is to provide a pair of slides to each of which is pivoted a lever having a dog or pawl for turning a plurality of leaf turning arms, such slides being operated either by hand, or 30 by foot pressure in turning the arms, and controlled by a pair of spiral springs for automatically returning the slides and the said levers into turning position.

35 A still further object of the invention is to provide a special casing for the arm-operating mechanism, specially shaped turning arms, cord and pulley connections within the casing and extending therefrom for operating such mechanism either by hand, or 40 by foot pressure, and a protecting apron attached to and extending from the casing.

45 Various other objects, advantages, and improved results are attainable in the practical application and operation of the invention hereinafter to be fully described.

In the accompanying drawings forming part of this application: Figure 1 is a front view of the device with a portion of the 50 protector broken away. Fig. 2 is a rear view of the rack. Fig. 3 is an enlarged section on the line X—X Fig. 1. Fig. 4 is a bottom view of the casing. Fig. 5 is an elevation with the front of the casing removed. Fig. 6 is an enlarged cross section on the line 55 Y—Y Fig. 5. Fig. 7 is a section on the line Z—Z Fig. 5. Fig. 8 is an enlarged section

showing one of the lever-dogs engaging a turning arm with the latter as in the act of being turned. Fig. 9 is a perspective view of one of the turning arms partly broken away showing it partly extended. Fig. 10 is a perspective view of one of the slides with its lever or dog. Fig. 11 is a side elevation of the tripod head. Fig. 12 is a perspective view of one of the tripod legs, 60 partly broken away, and its foot lever. Fig. 13 is an elevation of the casing folded.

The same reference numerals denote the 65 same parts throughout the several views of the drawings.

In carrying out our invention, we employ 70 a music rack 1, having projecting members or extensible wings 2, for holding a protector sheet 2^a, stretched over the front of the rack so as to entirely cover the same and prevent contact therewith of the music or 75 music book. Said protector is attached to an extension 3, of the back of the casing 4. The hollow standard 5, of the rack has a pair of pulleys 6, and a tripod head 7, is 80 attached to or formed on the lower end of the standard, and the tripod legs 8, are adjustably pivoted in such head by means of a slot 9, in the legs and pins 10, in the said head. The lower end of two of the 85 legs has an ear 12, to which is fulcrumed at 13, one end of a foot lever 14, the other end of the lever is connected to these legs by spiral springs 15, and the levers have a foot-piece 16, projecting therefrom in convenient 90 position to apply foot pressure for depressing the levers, and the function of the springs is to retract the levers. Said levers have a hook 17, to which are attached eyelet 95 straps 18, for connecting pull lines or cords 20 thereto. The cords 20, are connected with the pulley cords 21, by means of hooks 22 and eyes 23. The cords 21, extend over sheaves or pulleys 24, journaled in the casing and are attached to stems 25, of the slides 26, working in grooves 27, upon the inner 100 sides of the casing. Said stems are operated through and controlled by spiral springs 28, butting against guide brackets 29, and against plates 30, which connect the stems with the slides. The slides each have a lever 31, pivoted thereto at 32, and such levers are controlled in their movement by a plate 105 spring 33, attached to the slides. The levers 31, are provided with a pawl or dog 34, controlled in its outward movement by a spring 35, and the free end of said dogs or pawls is 110

provided with a hook head 36, adapted to engage the pivoted end of the leaf-turning arms 37, for lifting and turning said arms successively from one side to the other. The 5 arms 37 are pivoted on arm shaft 38, fixed within the casing.

The arms 37, all being of the same construction only one of them will be herein described in detail; such arm is L-shaped, the 10 short member 37^a of which extends into the casing and is provided with a pair of ears 39, for mounting the arm on the shaft 38, and the long member of the arm 37, has a finger 40, pivoted thereto and foldable there- 15 upon by means of a connecting link 41, and bar 42, the free end of the finger being pro- vided with a leaf grasping clamp 43. When the arms 37, are not in use they may all be thrown to one side of the shaft 38, and held 20 against the back or extension 3, of the casing by means of a keeper 44. The said back ex- tension 3, is provided with pins 45, which form a rest for sheet music or music books.

The means for operating the foregoing 25 described mechanism by foot pressure that the same may turn the arms 37, has been de- scribed, and in order to operate said mech- anism by hand, cords 46 are attached to the end of the stems 25, and extend over guide 30 sheaves 47, journaled in the casing and pro- ject through the bottom of the casing where such cords are provided with hand knobs 48.

The casing is divided centrally into two 35 parts which are hinged together at 49, so as to form an opening 49^a, and said parts are secured in lengthwise, operative position by means of a latch 50, or other similar device, which will permit the casing parts to be folded one upon the other when not in use, or 40 for packing and storing, or for transporta- tion. The bottom of the casing is provided with a pair of thumb-screw clamps 51, hav- ing followers or washers 52, between which, 45 projections 53, of the music rack are clamped for connecting the casing to such rack in op- erative position.

The leaf turning arms may be operated either by applying foot pressure to either of the foot levers for sliding one or the other 50 of the slides, and such sliding movement will pull and raise the dog lever with one of the leaf turning arms (for example one at the right of the rack) hooked in the dog head for raising said arm in circular move- 55 ment and swing or throw it over its pivot shaft, so that said arm will fall by gravity into proper position at the left of the rack. The same operation and result is accom- plished by pulling the hand knobs, and upon 60 releasing such pull or the foot pressure, the spiral springs 28, will automatically return

the slides so as to drop the lever, and per- mit the dog head to fall under or hook an- other leaf turning arm.

It will be observed that the foldability of 65 the arms and of the casing will permit the device to be conveniently set up and re- moved from place to place as may be de- sired, without other arrangement or manip- 70 ulation thereof, except the clamping of the same to the rack, connecting the hook and eyes, and then hooking the straps to the foot levers; and that such hooking of the straps may be varied according to the tension of 75 the foot springs and the springs 28, so as to produce proper and desirable working of the parts. When the leaf turning arms are in operation, the arm keeper is turned parallel with the casing.

It is obvious that the casing may be 80 clamped to the music rack or holder of pi- anos and organs, in which case the leaf turn- ing arms are operated by the hand knobs and their cords.

It will be understood that various changes 85 or modifications may be made in the manu- facture and practical application of the in- vention, within the scope of the appended 90 claim, and that we do not wish to be under- stood as limiting ourselves to any particular 95 size, shape or material, nor to any particu- lar number of leaf turning arms.

Having thus described our invention what 95 we claim as new and desire to secure by Let- ters Patent is:

The combination, with a music rack, a 100 tripod support for the rack, and a music leaf turner comprising a casing attachable to the rack, leaf turning arms journaled in the cas- ing and projecting therefrom, and mech- anism contained within the casing for turn- 105 ing the arms, of means for operating said mechanism comprising a pair of levers ful- erumed to the legs of the tripod and having hooked ends, a foot piece projecting from 110 the levers between the fulcrum and the hooked end of each, cords working through the head of the tripod, adjusting straps con- necting the cords with the levers, spiral 115 springs attached to the hooked ends and to the legs of the tripod so as to hold the levers and the straps substantially parallel with the legs, and cords working through the cas- ing and connecting the strap-cords with said mechanism.

In testimony whereof we affix our signatures in presence of two witnesses.
